13 Claims. (Cl. 66—174)

1

This invention relates to resilient fabrics and to garment structures composed completely or partly of such fabrics. In many garments it is desirable to construct the whole garment or portions of the garment from fabrics having a resilient characteristic in one or more directions. Thus, for the manufacture of girdles or corsets, for body support and as a foundation garment, certain areas or all of the garment can desirably be constructed of fabrics knitted from rubber-elastic yarns. Such elastic yarns are knitted under tension and after knitting the yarn tends to contract and the fabric accordingly assumes a smaller size in its relaxed condition than when under tension across the fabric. Such fabrics made of rubber-elastic yarns knitted under tension are well known and have a great usefulness but unfortunately are subject to relatively short life. However, at the present time knitted resilient or "stretchable" fabrics that are knitted from rubber-elastic yarn are the best that are available for use in such garments as girdles, in the waist bands of pajamas, shorts, wristlets and the like.

The principal disadvantage of fabrics knitted from rubber-elastic yarns is that the elastomer which is used as the resilient base of the yarn, whether of natural or synthetic type, is subject to short life and accordingly a garment composed of such materials may lose its "stretch" in a matter of months of wear or even during shorter times. Furthermore, the deterioration occurs on the shelf and in order to obtain the most service from such garments they must be merchandised and used within a reasonable time after being made. Such stretchable fabrics made of rubber-elastic yarns, regardless of whether the rubber is natural or synthetic, are particularly subject to deterioration due to laundering, for water and detergents markedly reduce the life of such elastic members. Since laundering is essential in the use of most fabrics that are used for body garments, this reduction in life of the garment due to laundering has had to be accepted as one of the inherent limitations of such fabrics.

It is an object of the instant invention to provide an improved stretchable fabric having long service life and to provide garments made of such fabric.

It is another object of the invention to provide elastic fabrics knitted from yarns composed of polyamide condensation products, said yarns being selected from a specified range of sizes and having a ratio of the number of filaments to the

2

denier size of the yarn in a specified ratio range.

It is another object of the invention to provide a knitted elastic fabric of long life and serviceability.

It is also an object of the invention to provide garments composed in whole or in part of the aforesaid fabrics.

The invention is illustrated with reference to the drawings in which corresponding numerals refer to the same parts and in which

Figure 1 is a fragment of a representative fabric made in accordance with the instant invention;

Figure 2 is a front elevational view of a man's short having an elastic waist band composed of the fabric of the instant invention;

Figure 3 is a front elevational view of a pajama trouser or other trouser element for men, women and children having a waist band composed of the elastic knitted fabric of the instant invention;

Figure 4 is a fragmentary view showing a portion of a sleeve having a wristlet composed of the knitted elastic fabric of the instant invention;

Figure 5 is a fragmentary sectional view showing the sleeve with an inner wristlet composed of the elastic knitted fabric of the instant invention;

Figure 6 is a front elevational view of a lady's corset or girdle composed of the fabric of the instant invention. In this view the left leg of the corset is shown in pattern view, the right half of the garment is folded and deflected so as to permit the left half to lie flat. In Figure 6 the right half of the corset would assume approximately the shape shown by the dotted lines if not so deflected;

Figure 7 shows a glove having a wristlet composed of the elastic fabric of the instant invention;

Figure 8 shows a front elevational view of a man's casual short having a gathered waist band; the inner elastic portion of which is composed of the knitted elastic fabric of the instant invention;

Figure 9 is a sectional view of the waist band of the garment shown in Figure 8, taken along the line and in the direction of arrows 9—9 of Figure 8.

In carrying out the invention there is utilized yarns composed of linear condensation polymers made in accordance with one or more of the following patents: 2,071,250 through 2,071,253; 2,130,523; 2,130,948; 2,149,286 and 2,149,273.

Fiber forming polyamide yarns, such as nylon, have especial usefulness in this invention. Throughout this specification and in the claims, the term "linear condensation polymer yarns" will be understood to include yarns made in accordance with the aforesaid patents and more especially fiber forming polyamide yarns, such as nylon yarns.

In carrying out the invention the fabric is knitted utilizing such linear condensation polymer yarn having a denier size in the range of 100 to 300, said yarns being composed always of a plurality of filaments. The number of filaments in the yarn must be such that the ratio of the number of filaments divided by the denier size number is in the range from 0.02 to 0.15. Best results are obtained when the ratio of the number of filaments in such yarn to the denier size number is in the preferred range of 0.03 to 0.10. The knitted fabric is preferably a 1 x 1 rib knit fabric, but other knitted fabrics, such as the Swiss knit fabric may also be used, although the 1 x 1 rib knit fabric is preferred because of its inherent greater stretch transversely of the direction of knitting.

Thus, in accordance with the invention the fabric may be knitted from yarns composed of the stated linear condensation products in the size range from 100 to 300. For example, denier sizes 100 having from 2 to 15 filaments in each yarn are satisfactory where minimum elasticity transversely of the fabric is desired. Where a greater elasticity transversely of the fabric is desired, the denier size of the yarn is increased, for example yarns of 200 denier size and having a number of filaments ranging from about 4 to about 30 may be utilized. Likewise, where still greater elastic strength is needed, yarns of size 250 denier and having a number of filaments from about 5 to about 38-40 are satisfactory. For maximum transverse elastic strength, yarns of 300 denier size are utilized having a number of filaments ranging from about 5 to about 45. It will be appreciated that the number of filaments in the yarn may be varied somewhat out of the stated ranges and likewise slightly larger or smaller denier sizes than those stated may be utilized. For best results, however, the ratio of the number of filaments to the denier size number should be held in the approximate range of 0.02 to 0.15 and the denier size should be from about 100 to about 300.

For most garments, such as the waist bands on men's shorts, girdles or corsets or the like, the elastic fabric can be knitted from nylon yarn of 260 denier having 17 filaments with excellent results and the fabric used in single or multiple thickness depending upon the degree of elasticity and support needed. Thus, for the men's short shown in Fig. 2 the main body of the garment generally designated 10 is composed of cotton or rayon knitted fabric 11 which has no resiliency worthy of mention. The garment fabric 11 has a stretchiness at the waist band area in the direction of the double arrow 12 but the inherent resiliency of cotton, rayon or similar knitted fabrics is insufficient to maintain the garment in place on the wearer without utilizing some additional support by way of a special waist band. Accordingly, it has been customary to provide a waist band at 15 which is woven from yarns composed of rubber elastic, such fabrics being woven with the rubber-elastic yarn under tension. In accordance with this invention the waist band 15 is composed of a fabric knitted from yarns composed of linear condensation

polymer having a denier size in the approximate range of 100 to 300 and a number of filaments such that the ratio of the number of filaments divided by the denier size of the particular yarn is in the range of about 0.02 to 0.15. The waist band 15 in the garment shown in Figure 2 is made double by taking a portion of the fabric and folding it over so that the fold comes at the upper edge 16. The two cut portions of the fabric are then stitched to the main body of the garment by means of an elastic stitch along the lines 17, it being understood that such stitching 17 is of any style which will stretch in the direction of stitching (i. e. in the direction of double arrow 12). Thus, a triple interlock stitch is very satisfactory for covering the cut edges of the waist band fabric 15 and at the same time fastening such waist band to the main body of garment 10. The waist band is thus permitted to stretch in the direction of the double arrow 18.

The direction of knitting of the fabric in the waist band 15 is in the direction of the double arrow 19. Thus, the length (or direction of knitting) of the knitted fabric runs up and down in respect to the garment 10. More explicitly, the fabric shown in Figure 1 readily stretches in the direction of the double arrow S (which is transverse to the direction of knitting of the fabric) and stretches very little in the direction of double arrow NS, which is the direction the fabric was knitted. Accordingly, when the fabric of Figure 1 is used in a garment, it is laid so that the direction S will correspond to the direction in the garment in which resiliency is desired.

By using a folded over piece of such fabric at 15 and by attaching it to the main body of the garment in a distended condition by means of an elastic stitch, the waist band 15 is permitted to contract to its relaxed position, as shown in Figure 2. However, when applied to the wearer the waist band 15 stretches out and assumes a position as determined by the size of the wearer's waist. However, unlike the prior elastic waist bands that are woven with rubber-elastic, the resilient fabric of the instant invention does not have a quick elastic-recovery to its initial size and hence does not pull against the wearer with the same unrelenting force as is characteristic of fabrics woven with rubber-elastic yarns. Thus, for example, a size 36 man's "short" of the pattern shown in Figure 2 made in accordance with the present invention, the length of the waist band is 24 inches (or 12 inches as measured across the dimension W of the garment shown in Figure 2). In an exemplary case the wearer had a body size of 36 inches around the waist and wore a garment such as that shown in Figure 2, which accordingly distended the waist band 15 to the 36-inch dimension. When removed from the wearer the waist band of such garment contracted within a few minutes to 32 inches (that is to say 16 inches across the dimension W of Figure 2) but when the garment was permitted to remain off the wearer, however, as for example when the garment was removed at night and then measured the following morning, the waist band was then found to have contracted to its original 24-inch size (12 inches as measured across the dimension W) which is the proper dimension for a size 36 garment. Thus, the immediate elastic recovery is slower, which is an advantage, for it makes the garment "feel" better and yet the ultimate elastic recovery is invariably to the proper size of the garment. Furthermore, such elastic characteristics

continue throughout the life of the garment, even outwearing cotton and synthetic fabrics of which remaining portions of the garment are constructed.

In Figure 3 there is illustrated another form of similar pants or trouser garment, in this instance a pajama 28, the main body 28 of which is constructed of knitted or woven fabric according to any desired pattern. In this instance also the waist band 22 of the garment is composed of one or more plies of fabric knitted in accordance with the present invention. Attachment of the waist band 22 is by means of a line of stitching 23 which is resilient in the direction around the garment, such stitching being a triple interlock or similar stitch. The fabric composing the waist band 22, as previously described, is attached to the fabric so that the direction of knitting of fabric is up and down, as shown in Figure 3, by the direction of arrow 24, whereas a direction transverse to the direction of knitting of the fabric (corresponding to direction S of Figure 1) is in the direction of the dimension line 25 of the garment in Figure 3. The waist band in this instance also is made by folding over a piece of fabric so as to provide a double thickness, thus providing a rolled or folded edge along the top of the waist band at 26. If desired, however, the waist band may be knitted of single thickness with a self-edge at 26 and a ravel edge at 23 and the ravel edge sewed to the garment to which the waist band is applied.

The fabric forming the waist band or other elastic member of the garment may be knitted either as a tubular knit fabric or a flat knit fabric, the tubular knit being preferred for such applications as underwear, waistbands, wristlets, etc. The fabric is preferably knit in a variety of tubular sizes corresponding to the various garment sizes to which the fabric is applied, thus dispensing with any seams vertically through the fabric. However, such a vertical seam is of no particular disadvantage where it is desired to make a belt opening, the belt being otherwise resilient.

In Figures 4 and 5 there are illustrated two forms of sleeves in which a fabric of the instant invention is utilized with particular effectiveness. Thus, the sleeve 30 shown in Figure 4 is provided with an exposed wristlet at 31 which is attached to the main body of the sleeve by means of resilient stitching along line 32. Similarly, the sleeve 35 shown in Figure 5, which for example may be a jacket, coat or four coat sleeve, is provided with an inner wristlet 36 which is attached to the sleeve by means of the stitching 37.

In Figure 7 a wristlet 38 similar to those in Figures 4 and 5 is attached by means of the stitching 39 to a glove 40. The wristlets of Figures 4, 5 and 7 may very desirably be composed of fabrics made from the lower denier numbers in the range above specified and are preferably knitted as tubular fabrics and used double. A section of such fabric is cut off and folded over, the two cut edges being brought into juxtaposition with the fold as at 33 in Figure 4, 34 in Figure 5 or at 41 in Figure 7. The cut edges are then bound in place and sewed to the main body of the sleeve or glove by an overlock stitch or similar stitch which is stretchy in the direction of stitching, and binds the cut edges. Special advantage is achieved by utilizing the herein described fabrics for construction of girdles or corsets, such as illustrated in Figure 6. Thus, in the girdle shown in Figure 6 the garment is entirely composed of the resilient

fabric of the instant invention, the fabric being laid in the garment so that the direction NS of Figure 1 corresponds to the direction of arrows 50, 61, 62 and 63 of Figure 6. In Figure 6 the left half of the girdle generally designated 55 has been laid out flat as a pattern and the right half necessarily deflected so as to permit the left to lie flat. Thus, the girdle has a waist band 51-52-53. The fabric of the left half of the girdle is cut so that it lies along the pattern 51-52, thence along the center line 54 and which then curves at 56 to the crotch center 57, the pattern then extends along the curved line 58 which forms the inner seam on one leg to the point 59 and thence along the lower termination of the leg as the line 59-60. The direction of knit of the fabric is as shown by the dimension lines 50, 61, 62, 63 and a direction transverse to the fabric (corresponding to direction S of Figure 1) corresponds to the dimension lines 64 and 65. The latter dimension line 65 extends entirely across the left half of the garment and the right half of the garment and indicates the direction in which the garment is resilient. The waist line 51-52-53 is achieved simply by folding in the upper edge of the garment which is then stitched along the line 67-68 utilizing an overlock or double interlock stitch which is capable of stretching in the direction of the line of stitching. Likewise, the lower line of the leg 59-60 is also stitched along the line 69-70 with a similar line of stitching. A front garter support is supplied at 71 and a rear garter support at 72 for each of the two legs of the garment. The crotch of the garment is reinforced by inserting on the inside a second thickness of material which is stitched along the line 72-73-74-75-76. Such crotch insert may be dispensed with in light weight garments, if desired. It will be understood that the right half of the garment is an enantiomorphous duplicate of the left half and that in Figure 6 the right half has merely been deflected so as to permit the left half of the garment to show as a pattern. It will also be understood that the front elevation of the garment, as shown in Figure 6, and that the back portion of the garment including the seat may be cut slightly fuller than the front so as to allow sufficient room for the buttocks. The garment shown in Figure 6 has a considerable degree of elasticity across the garment, as in the direction of dimension lines 64-65 and around the legs and the waist of the garment. The elasticity in the direction of knitting of the fabric, that is to say along the dimension lines 50-61-62-63 is relatively small and the garment does not stretch materially in this direction. The center line seam 52-54-55-57 does not need to be materially elastic and any form of overcast stitch sufficiently strong to fasten the two portions of the garment together is satisfactory. The garment has excellent body retaining characteristics and yet does not exert the unrelenting tension exerted by the rubber-elastic type of knitted fabric. Thus, it is possible for the wearer, when wearing a garment such as that shown in Figure 6 made in accordance with this invention, to draw in and pull away from the garment slightly because the elastic recovery is not instantaneous. The garment does elastically recover to some extent relatively rapidly, but its complete elastic recovery does not occur until several hours after the garment has been removed. Thus, the foundation garment does exhibit a desirable principle not heretofore achieved in elastic foundation garments. Any area of the garment, such as the abdomen section may be made of multiple thick-

ness, to increase the degree of body support. Thus, the portion of the garment between lines 65 and 67 may be made in multiple thicknesses if desired.

In Figures 8 and 9 there is illustrated another form of garment made in accordance with the instant invention. In this garment, which is a man's casual short used as an outer garment, the main body of the garment generally designated 80 may be composed of woven or knitted fabric which in itself has no appreciable elasticity. The garment has a right leg portion 81 and a left leg portion 82 and has a fly opening at 83, the legs being terminated at 84 and 85, or they may be made longer or of full pant length, if desired. The waist band 87 of the garment is gathered in at 89 and is stitched to an internal waist band 90 composed of fabric made in accordance with the instant invention. Thus, referring to Figure 9 the fabric 90 is composed of two layers 91 and 92 folded together. The fabric 90 on the inside of the waist band is stretched to the full size of the waist band 87 and is then stitched along its upper edge 94 and its lower edge 95. These lines of stitching are a triple interlock stitch or any such form of stitch which is elastic in the direction of stitching. As soon as stitched, the garment is released and it recovers elastically, thus causing a number of convolutions 97 to be formed in the exterior fabric which is not elastic.

In many garments it is desirable to provide resilient sections or panels which only partially encircle the body or body member. Thus, in some corsets and girdles, resilient panels are provided at the sides and legs, the remainder of the garment being of non-resilient fabric. Likewise, in many waist band applications a part of the waist band, such as that part of the waist band around the back of the garment, may be made resilient, while the remainder is non-resilient. The woven fabric of this invention has especial usefulness in such applications for the fabric need only be sewed in with the direction transverse to the direction of wearing (direction "S" of Figure 1) arranged in the direction in which resilience (stretch) is desired to be provided. Thus, shorts, pants, girdles, and belt linings may be provided which provide a controlling resilience in the garment at the points desired, with assurance that the garment size will remain accurate throughout the life of the garment.

As many apparently widely different embodiments of this invention may be made without departing from the spirit and scope thereof, it is to be understood that I do not limit myself to the specific embodiments herein.

What I claim is:

1. In a garment having a resilient section, the improvement in which said section is formed of a rib knitted fabric in which the yarn is made up of a plurality of filaments composed of a linear condensation polymer, the size of such yarn being in the range of about 100 to 300 denier and the number of filaments in the yarn being selected so that the ratio of the number of filaments divided by the denier size number is in the range of 0.02 to 0.15.

2. In a garment having a resilient section, the improvement in which said section is formed of a rib knitted fabric in which the yarn is made up of a plurality of filaments composed of a linear condensation polymer, the size of such yarn being in the range of about 100 to 300 denier and the number of filaments in the yarn being se-

lected so that the ratio of the number of filaments divided by the denier size number is in the range of 0.03 to 0.10.

3. In a garment having a resilient section, the improvement in which said section is formed of a rib knitted fabric in which the yarn is made up of a plurality of filaments composed of a fiber forming polyamide, the size of such yarn being in the range of about 100 to 300 denier and the number of filaments in the yarn being selected so that the ratio of the number of filaments divided by the denier size number is in the range of 0.02 to 0.15.

4. In a garment having a resilient section, the improvement in which said section is formed of a rib knitted fabric in which the yarn is made up of a plurality of filaments composed of nylon, the size of such yarn being in the range of about 100 to 300 denier and the number of filaments in the yarn being selected so that the ratio of the number of filaments divided by the denier size number is in the range of 0.02 to 0.15.

5. A garment having a rib knitted fabric portion thereof for at least partially encircling a part of the wearer's body in an encircling direction, said knitted fabric portion being further characterized in that it is knitted from a multiple filament yarn composed of fiber forming polyamide material, the denier number of said yarns being in the range of about 100 to 300 and the number of filaments in the yarn being such that the ratio of the number of filaments divided by the denier size number is in the range of 0.02 to 0.15, said knitted fabric being oriented in the garment so that a direction transverse to the direction in which it is knitted corresponds substantially to said encircling direction.

6. A garment having a waist band, at least a portion of said waist band being composed of a rib knitted fabric knitted from a multiple filament yarn composed of fiber forming polyamide material the denier number of said yarns being in the range of about 100 to 300 and the number of filaments in the yarn being such that the ratio of the number of filaments divided by the denier size number is in the range of 0.02 to 0.15, said knitted fabric being oriented in respect to said waist band so that a direction transverse to the direction in which said fabric is knitted corresponds substantially to the direction in which the waist band extends.

7. The garment of claim 6 further characterized in that said waist band is knitted as a tubular knit fabric having a circumference corresponding to the waist band.

8. The garment of claim 6 further characterized in that said waist band is formed by folding a portion of said knitted fabric to form a folded edge, said folded edge being positioned so as to be the upper edge of the waist band.

9. A wrist encircling member comprising a rib knit fabric knitted from a multiple filament yarn composed of fiber forming polyamide material, the denier number of said yarns being in the range of about 100 to 300 and the number of filaments in the yarn being such that the ratio of the number of filaments divided by the denier size number is in the range of 0.02 to 0.15.

10. A waist encircling member comprising a tubular knit fabric rib knitted from a multiple filament yarn composed of fiber forming polyamide material, the denier number of said yarns being in the range of about 100 to 300 and the number of filaments in the yarn being such that the ratio of the number of filaments di-

vided by the denier size number is in the range of 0.03 to 0.10.

11. A girdle comprising a body encircling section, at least a portion of which is rib knitted from a multiple filament yarn composed of fiber forming polyamide material, the denier number of said yarns being in the range of about 100 to 300 and the number of filaments in the yarn being such that the ratio of the number of filaments divided by the denier size number is in the range of 0.02 to 0.15. 10

12. A pajama comprising a body encircling section, at least a portion of which is rib knitted from a multiple filament yarn composed of fiber forming polyamide material, the denier number of said yarns being in the range of about 100 to 300 and the number of filaments in the yarn being such that the ratio of the number of filaments divided by the denier size number is in the range of 0.02 to 0.15.

13. A garment having a rib knitted fabric portion thereof for at least partially encircling a part of the wearer's body, in an encircling direction, said knitted fabric portion being further characterized in that it is knitted from a mul- 25

tiple filament yarn composed of fiber forming polyamide material, the denier number of said yarns being substantially 260 and the number of filaments in the yarn being approximately 17, said knitted fabric being oriented in the garment so that a direction transverse to the direction in which it is knitted corresponds substantially to said encircling direction.
